UNITED STATES PATENT OFFICE

144,721

DESIGN FOR A UNIT HEATER

John Brandt Koch, Detroit, Mich., assignor to
American Blower Corporation, Detroit, Mich.,
a corporation of Delaware

Application September 14, 1945, Serial No. 122,082

Term of patent 14 years

(Cl. D81—10)

To all whom it may concern:

Be it known that I, John Brandt Koch, a citizen of the United States, residing at Detroit, in the county of Wayne and State of Michigan, have invented a new, original, and ornamental Design for a Unit Heater, of which the following is a specification, reference being had to the accompanying drawings, wherein:

Fig. 1 is a perspective view showing the front, side and bottom of a unit heater embodying my new design;

Fig. 2 is a perspective view showing the rear, bottom and other side thereof;

Fig. 3 is a front elevational view of the heater on a slightly reduced scale;

Fig. 4 is a side elevational view thereof on a similar scale; and

Fig. 5 is a rear elevational view thereof, also on a slightly reduced scale.

I claim:

The ornamental design for a unit heater, substantially as shown.

JOHN BRANDT KOCH.
